UNITED STATES PATENT OFFICE.

HERBERT W. CHENEY, OF MILWAUKEE, WISCONSIN, ASSIGNOR TO ALLIS-CHALMERS COMPANY, A CORPORATION OF NEW JERSEY.

CONTROLLER FOR ELECTRIC MOTORS.

No. 921,589.

Specification of Letters Patent. Patented May 11, 1909.

Application filed October 5, 1908. Serial No. 456,354.

To all whom it may concern:

Be it known that I, HERBERT W. CHENEY, a citizen of the United States, residing at Milwaukee, in the county of Milwaukee and 5 State of Wisconsin, have invented certain new and useful Improvements in Controllers for Electric Motors, of which the following is a full, clear, and exact specification.

My invention relates to starting controllers for electric motors, and particularly to returning devices for rendering such controllers fool-proof.

My present invention is an improvement on that set forth in my Patent No. 864,446, 15 granted Aug. 27, 1907. In such prior patent, there is described an arrangement which renders it impossible for a starting controller to be left in any starting position, thus making it impossible for a careless or inexperienced operator to leave a controller in a position in which a resistance or auto-transformer winding designed merely for use for but a few seconds is left in circuit indefinitely without care. The returning device described in such prior patent has been uniformly successful in its operation. My present invention, however, is an improvement on the device shown in such prior patent in that it biases the movable member of the 25 controller forward to off position when it has been moved forward beyond the running position. It also avoids the hammer-blow obtained in such prior device.

A controller constructed in accordance 35 with my present invention may be said to consist broadly of fixed and movable members, and means for biasing the movable member forward to off position during one part of its movement and backward to off 40 position during another part of its movement and leaving it unbiased at one point in its movement.

The specific novel features of my invention will appear from the description and 45 drawings, and will be particularly pointed out in the claims.

Figure 1 is a sectional view taken on the line 1—1 of Fig. 2 and showing a portion of a controller embodying my invention; Fig. 2 is 50 a front elevation of such portion of the controller, with the controller in off position; and Figs. 3 and 4 are somewhat similar views showing the controller in starting and running positions respectively.

55 The details of the starting controller proper

will not be fully described herein because they form no part of my present invention and are unnecessary to an understanding thereof.

The controller drum 10, in the present 60 case, is one which is arranged when in a starting position to connect a motor to poly-phase alternating current mains through step-down auto-transformer windings, and when in a running position to connect such 65 motor directly to such mains and to cut out the auto-transformer windings. The normal operation of this controller drum is continuously in the same direction, a movement 70 through 180° constituting a complete operation. The two opposite halves of the controller drum are identical in structure and coöperate respectively with two sets of contact fingers on opposite sides of the drum; each half coöperates in turn with each of the 75 two sets of contact fingers during successive complete operations of the controller. In the controller shown there is but one starting position between the running and the off 80 positions, but it is obvious that any desired number of such starting positions may be employed.

The controller drum 10 is operated by the handle 11, through gear wheels 12 and 13. On the common shaft of the handle 11 and 85 gear 12 is a casting 14, which consists of a mutilated gear 15 and cam arms 16. A member 17 pivoted at 18 has gear teeth 19 which coöperate with the teeth 15^a of the mutilated gear 15, and a roller 20 which co- 90 operates with the arm 16. The member 17 is biased in a clockwise direction by means of an adjustable spring 21. All of these parts are supported from the frame work 22 of the 95 controller.

When the controller is in off position, the parts are as shown in Fig. 2. The roller 20 is in engagement with the notch 23 of one of the arms 16, and through such engagement backward movement of the handle 11 and controller drum 10 is prevented. However, the drum 11 may be moved forward or in a clockwise direction, causing movement of the gear 13 and drum 10 in a forward or counter-clockwise direction. In this movement of the handle 11 and consequently of the casting 14, the member 17 is also forced in a counter-clockwise direction against the action of the spring 21. This movement of the member 17 is caused at first through 100 105 110

the engagement of the notch 23 and roller 20, and later through the engagement of the teeth 15^a and 19, these teeth having been brought into engagement during the early 5 part of the rotation of the members 14 and 17. In Fig. 3 where the parts are shown for a starting position of the controller, the teeth 15^a and 19 are in engagement. Should the operator release the handle 11 with the 10 controller in this position, the spring 21 will move the member 17 in a clockwise direction, and through such movement will cause the handle 11 and controller drum 10 to be returned to off position. Upon continued 15 forward movement of the handle 11, the teeth 15^a and 19 pass out of engagement and the roller 20 engages the end of one of the arms 16. This is illustrated in Fig. 4 which shows the arrangement of parts for a running 20 position of the controller. The parts are so shaped that when in this position the controller is without bias. Backward movement of the controller from this point is prevented because one of the teeth 19 is in 25 the path of a mutilated tooth of the gear 15, as illustrated. But forward movement is not prevented. When the handle 11 is moved forward from the position shown in Fig. 4, the roller 20 first passes over the outer 30 corner of the arm 16; whereupon the spring 21, through the engagement of the roller 20 with the cam surface 24 of the arm 16, gives the casting 14, and through it the handle 11 and drum 10, a bias forward to the off position, shown in Fig. 2. This off position is 35 180° away from the former off position. Should the handle 11 be released by the operator at any time in the movement of the controller before the roller 20 engages the 40 end of the arm 16, the movable parts of the controller will be returned automatically to the off position, through the action of the spring 21. Should the handle 11 be released by the operator at any time in the 45 movement of the controller after the roller 20 has engaged the surface 24 the movable parts of the controller will be moved forward automatically to the off position, through the action of the spring 21. But the handle 50 can be released when the controller is in running position, as indicated in Fig. 4, and there will be no tendency for the movable parts of the controller to move either forward or backward. Moreover, when the controller 55 is moved forward beyond the running position and the roller 20 slides down the cam surface 24 to the notch 23, the clockwise movement of the member 17 is somewhat retarded, and the roller 20 does not 60 come into the notch 23, which limits the clockwise movement of the member 17, with a hammer blow. This has been found to be of considerable advantage, both in lessening the noise of operation and eliminating the 65 shock to the controller.

Many modifications may be made in the precise arrangement here shown and described, and all such which do not involve a departure from the spirit and scope of my invention I aim to cover in the following 70 claims.

What I claim as new is:

1. A controller biased backward to off position when in a starting position, unbiased when in running position, and biased forward 75 to off position when beyond running position.

2. A controller for electric motors, comprising fixed and movable members, and means for biasing the controller backward to 80 off position during a part of its movement and forward to off position during another part of its movement, and leaving it unbiased at a point in its movement.

3. In a controller, contact fingers, a rotatable drum coöperating therewith, said drum having off, starting, and running positions, and a spring which tends to move the drum backward to off position when it is in starting position, to move the drum forward to off 90 position when it is beyond running position, and has no tendency to move the drum when it is in running position.

4. In a controller, a rotatable drum, fixed contacts with which said drum coöperates, 95 and means whereby said drum in different parts of its movement is biased in opposite directions to off position and is unbiased when in running position.

5. A controller for electric motors, comprising a rotatable drum, contact fingers co-operating therewith, means for preventing backward movement of said drum from certain positions, and a spring which tends to move said drum backward to off position 105 when it is in any position from which it may be moved backward and forward to off position only when it has been moved forward beyond running position.

6. A controller for electric motors, comprising fixed and movable members, said movable member having off and running positions, and means tending to move said movable member to off position in a direction away from the running position when 110 said movable member is on either side of such running position but exerting no influence to move said movable member when it is in such running position.

7. In a controller, fixed and movable members, a spring-pressed part tending to move said movable member backward to off position until it has reached the running position, and means for preventing said part from striking a hammer-blow when it ceases 115 to exert such tendency.

8. In a controller for electric motors, fixed and movable members, a spring-pressed part which tends to move the controller backward to off position when it is on one side of run- 120

130

ning position, and forward to off position when it is on the other side of running position, and means for preventing such part from striking a hammer-blow.

5 9. In a controller for electric motors, fixed and movable members, a spring-pressed part for giving a bias to said movable member during certain parts of its movement, and a mechanical connection between said part
10 and said movable member which during part

of the movement of the latter acts through a cam and during another part through a gear.

In testimony whereof I affix my signature, in the presence of two witnesses.

Milwaukee, Wis., Sept. 10, 1908.

HERBERT W. CHENEY.
